UNITED STATES PATENT OFFICE.

OTTO BUSSE, OF HETTSTEDT, GERMANY.

CASTING MOLD.

1,413,387.

Specification of Letters Patent. Patented Apr. 18, 1922.

Application filed August 16, 1921. Serial No. 492,782.

To all whom it may concern:

Be it known that I, OTTO BUSSE, a citizen of the German Republic, residing at 46 Bahnhofstrasse, Hettstedt, Germany, have 5 invented certain new and useful Improvements in Casting Molds, (for which I have filed application for patent in Germany January 18, 1918; Belgium July 10, 1920; France August 2, 1920; Great Britain July 10, 1920,) of which the following is a specification.

My invention relates to casting molds, and particularly to divided molds, the object of my invention being to provide a simple and 15 efficient structure having the advantages hereinafter pointed out or shown in the accompanying drawings in which—

Fig. 1 is a broken side elevation of a mold in which my invention is embodied in one 20 form;

Fig. 2 is a longitudinal section therethrough on the line 2—2, Fig. 1;

Fig. 3 is a side elevation of a modified construction; and

25 Figs. 4 and 5 are sections on the lines 4—4 and 5—5, Fig. 3, respectively.

It has heretofore been proposed to use 30 divided molds for casting metals and alloys, in which the sides of the mold are symmetrical so that by reversal both faces of each side plate may be used, in order to minimize warping and buckling of the plates. In these constructions the plates are secured in 35 position by angle pieces, the shanks of which are secured by screw bolts to the sides against which they lie. For this purpose the sides are provided with dovetail notches into which take the ends of the screw bolts.

The present mold comprises only a base 40 and two reversible side plates, each of which has at its opposite vertical margins, flanges offset in opposite directions, one of which, in assembled position, forms one end of the mold form. The construction presents the 45 convenience that in the first place the mere clamping of the two plates together forms the complete mold, and in the second place, the mere longitudinal shifting of one plate with respect to the other, forms a mold cavity of different width.

As shown in Figs. 1 and 2, the mold comprises a base plate *u* and the two symmetrically shaped side plates *a* and *b*. The side plate *a* has at its margins the two oppositely

faced marginal flanges *a'* and *a''*. Similarly the plate *b* is provided with like flanges *b'* and *b''*. When the two plates *a* and *b* are faced against each other, the respective marginal flanges *b'* and *a''* form not only the ends of the mold chamber *c*, but the spacers 55 which determine the thickness of the base plate.

The base plate *u* is provided with an upstanding rim *w*. Against the inner face *v* of this rim bears the marginal flange *a'* of the plate *a*, while a filler block *m* of like 60 measure is arranged between the rim and the margin of the plate.

Four posts *d* and *f* are carried by the base plate *u*. On the posts *d* are two cross bars 65 *e*, one arranged about half way up the posts and the other near the top, and both being held in position by securing rings *z*. Associated with the ends of the cross bars *a* are side arms *g*, which are engaged with both 70 the posts *d* and *f* and extend slightly beyond the latter. These extensions are slotted to receive the two further cross bars *h*, with which the projections are united by the bolts *i*. In these cross bars *h* are mounted clamping 75 screws *k* which bear against the plate *b*. By tightening these screws the two plates are pressed rigidly together to constitute the mold form adapted to receive the pour 80 in its chamber *c*.

After the casting has been removed on 85 the opening of the form, the plates *a* and *b* are reversed in position to present their opposite faces to the mold chamber *c* in contact with the molten metal of the following 90 pour.

In the modification shown in Figs. 3, 4, 5, the plate *a* is provided at its lower end with a dovetail rib *n* which takes into a channel *o* of corresponding shape in the base *p*, and 95 is thus held upright. In order to clamp the plates together, two stirrups *q* and *x* are slipped over the plates and carry tapped sockets *r* through which screw the clamping bolts *k*. The lower stirrup rests on angle 100 brackets *s* secured to the side margins of the plates *a* and *b*, while the upper stirrup, which is of less width, rests on the narrow stops *t*, over which the stirrup *x* freely passes.

105 Obviously the reversibility and lateral adjustability of the plates *a* and *b* is the same as in the construction first described.

Various modifications in detail of construction and arrangement of parts will readily occur to those skilled in the art, which do not depart from what I claim as 5 my invention.

I claim—

A mold comprising a pair of reversible

side plates having at their margins oppositely offset flanges forming the end closures of the mold chamber on the juxtaposition of 10 said plates.

In testimony whereof I have signed my name to this specification.

DR. OTTO BUSSE.
